UNITED STATES PATENT OFFICE.

HENRY BOUCHARD, OF AUSTIN, TEXAS.

TROLLEY-POLE.

No. 880,963.

Specification of Letters Patent.

Patented March 3, 1908.

Application filed April 16, 1907. Serial No. 368,513.

To all whom it may concern:

Be it known that I, HENRY BOUCHARD, a citizen of the United States, and resident of Austin, in the county of Travis and State of Texas, have invented an Improved Trolley-Pole, of which the following is a specification.

My invention is an improvement in trolley poles, and consists in certain novel constructions and combinations of parts herein-after described and claimed.

Referring to the drawings forming a part hereof, Figure 1 is a perspective view of a part of a car provided with my improved pole, 15 showing the position taken by the pole when the wheel engages the trolley wire. Fig. 2 is a similar view showing the position taken by the pole when the wheel is disengaged from the wire. Fig. 3 is a detail side view of 20 a part of the pole in one position. Fig. 4 is a similar view showing the pole in another position. Fig. 5 is a detail perspective view of the stand and a portion of the pole. Fig. 6 is a side view partly in section.

25 In the present embodiment of my invention, the trolley stand A, comprises a base a secured to the car E and having rotatably mounted therein the stud a⁹, to which is rigidly secured the projecting arm a⁴. The 30 bracket a' is provided with ears a² on each side of the stud, and the ears are pivoted to the stud by means of the pins a³.

The bracket a' is substantially circular in shape and is provided with a recess a⁷ for 35 a purpose to be hereafter described. The pole B comprises a plurality of telescoping sections b, b', the section b being provided with a pin b⁸ engaging a recess b⁹ in the section b', and a spring b³ is interposed between 40 the section, the pin b⁸ being provided with oppositely projecting trunnions b⁴, engaging slots b⁵ in the sides of the recess, whereby to prevent the displacement of the sections. The section b is provided near the end there- 45 of with trunnions b¹⁰ journaled in the bracket a', and the end of the section below the trunnions is adapted to be received within the recess a⁷ of the bracket.

A sleeve C is slidably mounted on the 50 bracket, and is adapted to move over the recess and the end of the section b contained therein to retain the pole in alinement with and in fixed relation to the bracket. Levers c² are journaled on each of the trunnions b¹⁰, 55 and links c connect one end of each of the levers with the sleeve, the opposite ends of

the levers being connected by links c³ with the outermost section b' of the pole.

It will be understood from the description that when the pole is moved into alinement 60 with the bracket, and the extended end of the section b is engaged with the recess, the levers c² are rocked slightly on the trunnions enough to bring them out of line with the links but not enough to move the sleeve over 65 the extended end of the section b within the recess. When, however, the wheel b⁷ of the pole is engaged with the trolley wire F, the sections of the pole are moved towards each 70 other against the resistance of the spring, thus rocking the levers into the position shown in Figs. 1 and 3, and moving the sleeve upward over the recess to engage the extended end of the section whereby to retain the pole in alinement with the bracket 75 and in fixed relation with respect thereto, it being understood that the spring b³ is not strong enough to overcome the resistance of the trolley wire.

Should the wheel become disengaged from 80 the trolley wire, the spring b³ will force the sections apart, thus rocking the lever c² on the trunnions and moving the sleeve C from over the recess and from engagement with the extended end of the section b, thus permitting the pole to drop into the position shown in Figs. 2 and 5, and preventing the engagement of the pole with guy wires and the like.

One of the links c³ is extended forwardly 90 as at c⁵, and to the extension is connected one end of a rope or cable D, the said rope passing downward over a pulley b⁶ journaled in the lower end of the innermost section b of the trolley pole, and rearwardly over a pulley 95 a⁸ journaled on the bracket a', the opposite end of the rope being connected to the pole as at b¹¹, adjacent to the trolley wheel b⁷, the rope being of sufficient length so that the middle portion thereof extends to the rear 100 platform of the car.

A rest a⁶ is arranged on the bracket a' for receiving the pole when it is in the position shown in Figs. 2 and 5, and a spring a⁵ is connected with the arm a⁴ and with the 105 bracket a', whereby to normally retain the bracket in the erect position.

In operation, when it is desired to engage the trolley wheel with the trolley wire, traction is made on the end of the rope D connected with the innermost section b to bring 110 the pole into the position shown in Fig. 4.

The opposite end of the pole is now manipulated through the end of the rope attached thereto to bring the trolley wheel into engagement with the wire, and when 5 this is done, the pressure of the wire moves the sections toward each other, thus moving the collar C over the recess and into engagement with the end of the innermost section.

It will be evident from the description, 10 that the pole is extensible and contractible, and that the means for retaining the pole in alinement with the bracket and in fixed relation with respect thereto, is operated by the extension and contraction of the pole, the 15 extending of the pole acting to release the retaining means.

In Fig. 5 the rest a^6 is replaced by a loop b^7 pivoted to the bracket and engaging the 20 end of the pole section b , a lug b^7 being arranged on the pole section to limit the motion of the loop.

I claim:

1. The combination with the supporting bracket, of a trolley pole comprising a plurality of telescoping sections, the innermost section being provided with trunnions, near one end thereof for engaging the bracket, said bracket being recessed for receiving the end of the section, a sleeve slidable on the 30 bracket, levers pivoted on the trunnions, a connection between one end of each of the levers and the sleeve, a connection between the other end of each of the levers and the outermost section of said pole, and a spring 35 interposed between the sections for normally retaining them in extended position, whereby to move the sleeve from over the end of the section to release it from the recess.

40 2. The combination with the supporting bracket, of a trolley pole comprising a plurality of telescoping sections, the innermost section being provided with trunnions, near one end thereof for engaging the bracket, said bracket being recessed for receiving the end of the section, a sleeve slidable on the bracket, a connection between the sleeve and its outermost section, whereby to move said sleeve from over the end of the section when 45 the sections are moved apart, and a spring normally acting to move the sections apart.

3. The combination with the bracket, of a trolley pole comprising a plurality of telescoping sections, one of said sections being 55 hinged to the bracket, means for retaining the pole in alinement with the bracket, a con-

nection between the other section and the retaining means, whereby to release said retaining means when the sections are extended, and a spring acting normally to extend 60 the sections.

4. The combination with the bracket, of a trolley pole pivoted to the bracket, said pole comprising a plurality of telescoping sections, means for retaining the pole in alinement 65 with the bracket, means whereby the extending of the sections will release the retaining means, a spring acting normally to extend the sections, and a cable having its ends connected with the ends of the pole whereby 70 to manipulate the same.

5. The combination with the bracket, of a trolley pole pivoted to the bracket, said pole comprising a plurality of telescoping sections, means for retaining the pole in alinement 75 with the bracket, means whereby the extending of the sections will release the retaining means, a spring acting normally to extend the sections, and a rest on the bracket for supporting the pole when out of alinement 80 with the bracket.

6. The combination with the bracket, of a trolley pole pivoted to the bracket, said pole comprising a plurality of telescoping sections, means for retaining the pole in alinement 85 with the bracket, means whereby the extending of the sections will release the retaining means, and a spring acting normally to extend the sections.

7. The combination with the bracket, of a 90 trolley pole pivoted to the bracket, said pole comprising a plurality of telescoping sections, means for fixing the pole with respect to the bracket, means whereby the extension of the pole will release the retaining means, and a 95 spring acting normally to extend the pole.

8. The combination with the trolley stand, of an extensible pole pivoted thereto, means for fixing the pole with respect to the stand, means whereby the extension of the pole will 100 release the fixing means, and means acting normally to extend the pole.

9. The combination with the trolley stand, of an extensible pole pivoted thereto, means acting normally to extend the pole, and 105 means whereby the contraction of the pole will fix said pole with respect to the stand.

HENRY BOUCHARD.
